UNITED STATES PATENT OFFICE

2,119,360

BOX OR CARTON

Frank J. Schleicher, University City, Mo.

Application May 18, 1936, Serial No. 80,299

2 Claims. (Cl. 229—6)

This invention relates to boxes or cartons, and has special reference to boxes or cartons made of cardboard or the like.

An object of the invention is to provide an improved box or carton having a bottom wall provided with integral or attached upward extensions along its margin confined between and attached to inner and outer wall forming plies whereby the outer wall and the bottom wall are 10 securely connected.

The lid of the box may also be formed in a similar manner so that the side wall of the lid will telescope about the side wall of the lower portion of the box or carton.

15 Other objects of the invention will be readily apparent from the following description, reference being made to the annexed drawing, in which—

Fig. 1 is a plan view showing the inner side of the outer wall before the same is folded or shaped for attachment to the top or bottom wall of the box or carton.

Fig. 2 is a plan view of a wall constructed for use to form the bottom wall or the top wall of the box or carton.

Fig. 3 is a perspective view in section and with parts broken away of a portion of the box or carton.

Fig. 4 is a perspective view in section and a part broken away showing another portion of the box or carton.

Fig. 5 is a vertical cross-sectional view of a complete box or carton made in accordance with this invention.

35 Fig. 6 is an enlarged sectional view showing a portion of the lid and a portion of the lower part of the box or carton.

The side wall shown in Fig. 1 comprises a strip 1 of cardboard or the like forming the outer surface of either the lid or the lower part of the box. Said strip has an inturned margin 2 folded against and attached to the inner side of said strip 1 and which may be provided with a decorative stripe 3.

40 The wall 4 is designed and adapted to form either the bottom wall of the box or the top wall 4' of the lid of the box. As shown, the wall is substantially heart-shaped, although it may be made in any desired shape and is provided with a series of integral or attached tongues or fingers 5 extending from its edge and adapted to be folded at right angles to the wall 4 against the inner surface of the wall formed by the strip 1 and below the edge of the marginal portion 2 of said strip. The wall 1 is attached to the tongues or

fingers 5 by glue or other appropriate fastening means so that the two walls 1 and 4 will be held securely together. The edge of the wall 1 is in alinement with the outer surface of the wall 4, thereby strengthening the corner. The tongues or fingers 5 are of approximately the same thickness as the infolded ply 2 (Fig. 3) and terminate adjacent to the edge of said ply 2. A strip 6 is attached to the inner surfaces of the tongues or fingers 5 entirely around the inside of the box 10 and covers said tongues or fingers and constitutes an additional reinforcement and ornamenting device. The strip 6 has one edge seated against the wall 4 and the opposite edge approximately in alinement with the edge of the 15 infolded ply 2.

An alternative construction is shown in Figs. 4 and 6. As there shown, a wall 1' is attached to the tongues or fingers 5 and has its edge in alinement with the exposed surface of the wall 4. Instead of forming an inturned ply 2 integral with the wall 1', a separate strip 7 is attached to the inner surfaces of the tongues or fingers 5 and to the inner surface of the wall 1' beyond the tongues or fingers 5, said strip extending the full width of the wall 1' and having its exposed edge in alinement with the exposed edge of said strip 1'.

A box of this construction may be manufactured at comparatively low cost and is strong 30 and durable. The ends of the wall 1 may be attached by an interlocking arrangement 8 or otherwise, as desired. The construction may be varied within the scope of equivalent limits without departure from the nature and principle of 35 the invention.

I claim:—

1. A box or carton comprising a bottom wall, fingers integral with the margin of said bottom wall and extending vertically and having cut-out 40 notches between them of increasing width from the margin of said bottom wall to the upper ends of said fingers, a curved enclosing wall surrounding said bottom wall and being vertical throughout its width and attached to the outer surfaces of said fingers and leaving said fingers offset inwardly from the entire inner surface of said enclosing wall, and an elongated curved strip attached to the inner side of and covering said fingers and having its lower edge seated upon 45 said bottom wall throughout the length of said strip and its upper edge approximately in alinement with the upper ends of said fingers throughout the length of said strip.

2. A box or carton comprising a bottom wall, 50

5 fingers integral with the margin of said bottom wall and extending vertically and having cut-out notches between them of increasing width from the margin of said bottom wall to the upper ends 5
10 of said fingers, a curved enclosing wall surrounding said bottom wall and being vertical throughout its width and attached to the outer surfaces of said fingers and leaving said fingers offset inwardly from the entire inner surface of said enclosing wall, an elongated curved strip attached to the inner side of and covering said fingers and having its lower edge seated upon said bottom

wall throughout the length of said strip and its upper edge approximately in alignment with the upper ends of said fingers throughout the length of said strip, and an inwardly and downwardly turned marginal portion integral with the upper 5 edge of said enclosing wall and attached to the inner surface thereof and having its lower edge terminating adjacent to the upper ends of said fingers and the upper edge of said first named strip. 10
